UNITED STATES PATENT OFFICE.

WILLIAM P. FEST, OF SOUTH BEND, INDIANA, ASSIGNOR TO THE STUDE-
BAKER BROS. MANUFACTURING COMPANY, OF SAME PLACE.

CARRIAGE-TOP.

SPECIFICATION forming part of Letters Patent No. 247,550, dated September 27, 1881.

Application filed July 26, 1881. (No model.)

To all whom it may concern:

Be it known that I, WILLIAM P. FEST, a citizen of the United States, residing at South Bend, in the county of St. Joseph and State of Indiana, have invented certain new and useful Improvements in Carriage-Tops; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to an improvement in canopy-tops for vehicles; and its objects are to dispense with a certain top-joint, usually necessary in bowed vehicle-tops, to facilitate the spreading and stretching of the top, and to construct a top of great lightness and strength.

I attain these objects by the means illustrated in the accompanying drawings, in which—

Figure 1 presents a side view, in elevation, of a carriage-top, showing, in connection therewith, the improvements, and, by dotted lines, the operation of the false bow and the position and appearance of top when collapsed. Fig. 2 shows a rear elevation of the top, with the same partly lowered.

A represents the seat or body, to which the bows B C are hung by a common joint, *d*, in the usual or other convenient manner. The bows B C are also pivoted at *e e* to a semi-top frame composed of two transverse bows, E E. These two parts of the said frame are united at the center of the top at *f*, and also at the same point are pivoted the supplementary or false bow G and the jointed upright brace H. The ends of the said false bow G, bent at right angles therewith, form the pivots on which the two parts of the frame E E, sleeve K, and brace H are hung, as shown in Fig. 2, and by which construction the united parts are free to turn independently of each other or together.

The false bow G constitutes the center of the arrangement of bows, and the semi-trans-

verse frames E E collapse upon it, together with the bows B and C, when the top is folded together. The bow G always preserves its relative position to the common joint *f*, thereby insuring an equal and uniform draw or extension to the material with which the top is trimmed.

By uniting the jointed brace H with the other parts at *f*, as described, one or more additional top-joints, generally employed on bowed vehicle-tops, and usually located on the transverse bow between the front and the back bow, are dispensed with.

By my construction, as may be readily seen, the top-drop may be wholly or partly collapsed and the same spread and stretched, as desired, in the most satisfactory manner.

The upright bows B C, the frames E E, and false bow G may be made of wood or metal, and when of metal the said frames and bow may be made tubular, as of gas-pipe, whereby great strength and lightness will be gained.

Having thus described my invention, what I claim, and desire to secure by Letters Patent, is—

1. A canopy-top for vehicles, consisting of the combination of bows, jointed side braces, a semi-top frame, and a false bow, the said frame, false bow, and jointed braces being pivoted at a common center, substantially as described.

2. A canopy-top for vehicles, provided with a false bow pivoted to a semi-top frame, substantially as described.

3. The combination, with a vehicle-body, of bows B C, jointed brace H, top-frame E E, and false bow G, substantially as described.

4. The combination of the semi-top frame, false bow, and jointed side braces, substantially as described.

In testimony whereof I affix my signature in presence of two witnesses.

WILLIAM P. FEST.

Witnesses:

W. MACK,

A. H. KELLEY.
